UNITED STATES PATENT OFFICE.

ERNEST CLAY, OF HOLDREGE, NEBRASKA.

MAIL-BOX MONEY-HOLDER.

1,089,827.

Specification of Letters Patent.

Patented Mar. 3, 1914.

Application filed September 11, 1912. Serial No. 719,826.

To all whom it may concern:

Be it known that I, ERNEST CLAY, a citizen of the United States, residing at Holdrege, in the county of Phelps and State of Nebraska, have invented new and useful Improvements in Mail-Box Money-Holders, of which the following is a specification.

This invention relates to mail box money holders, the object in view being to provide 10 a simple device of the class described, which may be manufactured at a minimum expense and applied to any mail box, so as to receive and hold change necessary to pay postage; said change to be collected by the 15 postman at the time he collects the mail.

With the above and other objects in view, the invention consists in the construction, combination and arrangement of parts, as will be hereinafter more fully described, 20 illustrated in the accompanying drawings, and pointed out in the claim hereunto appended.

In the drawings: Figure 1 is a perspective view, showing the device applied to a mail 25 box. Fig. 2 is a vertical sectional view of the holder. Fig. 3 is a plan view of the blank from which the main body of the holder is formed. Fig. 4 is a plan view of the shutter blank. Fig. 5 is a detail view 30 of the spring catch. Fig. 6 is a detail view of the signal.

The holder contemplated in this invention comprises a cylindrical body 1, attaching flanges 2 extending tangentially in opposite directions from the rear side thereof, a bottom shutter 3 hinged to the money holder, and a spring catch 4 secured to the cylindrical body of the holder, and provided with a shoulder 5 adapted to snap under the shutter and hold the same in close relation to the bottom of the receptacle. The device also comprises a signal 6 shaped to resemble a flag and pivotally connected, at 7, to the front side of the holder, so 45 that it may be drawn to a vertical or horizontal position to indicate whether the holder is empty or contains money.

The main body of the device is formed of a single sheet metal blank, shown at 8 in

Fig. 3, said blank having a width equal to 50 the height of the cylindrical body, and a length equal to the circumference of the cylindrical body and the flanges by means of which the device is attached to a mail box, as shown in Fig. 1. This blank, shown in 55 Fig. 3, is provided with slits 9 and 10 extending inward from the opposite longitudinal edges thereof, so that when the blank is rolled into cylindrical form, the end portions of the blank may be made to intersect 60 through the slits 9 and 10, the end portions beyond said slits forming the attaching ears hereinaabove referred to. In addition, the blank embodies the laterally projecting tabs 11 which are rolled into the 65 form of sleeves to form knuckles 12 to receive the hinge pin 13, by means of which the shutter is connected to the holder. The shutter shown in detail in Fig. 4 is also provided with a rearwardly extending tab 14 70 which is rolled to form a complementary hinge knuckle 15 which is interposed between the knuckles on the attaching flanges to receive the same hinge pin 13. At its opposite side, the shutter is cut away or provided 75 with a notch 16 to receive the spring catch 4 above described.

From the foregoing description, it will be seen that the main body of the device, including the cylindrical holder and the attaching flanges, is formed in one piece from a single sheet metal blank, thereby economizing materially in the cost of production and manufacture of the device. In fact, the entire device, with the exception 85 of the hinge pin, is formed of sheet metal.

What is claimed is:

A money holder attachment for mail boxes, comprising a cylindrical receptacle open at the top and bottom, a hinged shutter for closing the bottom of said receptacle, a spring catch on the receptacle for holding the shutter closed, and attaching flanges for fastening the holder to a mail box, the receptacle attaching flanges being 90 formed of a one piece sheet metal blank provided with slits extending inwardly from the opposite edges thereof in spaced relation 95

to each other, the portion of the blank between the slits being rolled into the form of a cylinder, and the opposite end portions of the blank being crossed so as to intersect 5 in line with said slits leaving the portions beyond the slits extending in opposite directions in a common plane.

In testimony whereof I affix my signature in presence of two witnesses.

ERNEST CLAY.

Witnesses:

OSCAR A. SWANSON,
SIDNEY PIERCE.
